US0D1020902S

(12) United States Design Patent (10) Patent No.: US D1,020,902 S
(45) Date of Patent: * Apr. 2, 2024

(54) SPORT-THEMED CASINO GAMING CLOTH

(71) Applicant: HMD Entertainment, LLC, Fairport, NY (US)

(72) Inventor: Ronald J. Wolff, Fairport, NY (US)

(73) Assignee: HMD Entertainment, LLC, Pittsford, NY (US)

() Term: 15 Years

(21) Appl. No.: 29/725,784

(22) Filed: Feb. 27, 2020

Related U.S. Application Data

(63) Continuation-in-part of application No. 15/796,761, filed on Oct. 28, 2017, now abandoned.

(57) CLAIM

I claim the ornamental design for a sport-themed casino gaming cloth, as shown and described.

DESCRIPTION

The FIGURE is a top plan view of a sport-theme casino gaming cloth embodying my new design.

The bottom surface and the side surfaces are not shown and do not form any part of the claimed design.

1 Claim, 1 Drawing Sheet
